F / G. 3

F / G. 4

F / G. 5

F / G. 6

FIG. 1 is a side view of a flashlight showing my new design;

FIG. 2 is a top plan view thereof;

FIG. 3 is a front elevational view thereof;

FIG. 4 is a rear elevational view thereof;

FIG. 5 is an opposite side elevational view thereof of FIG. 1; and

FIG. 6 is a bottom plan view thereof.

I claim:

The ornamental design for a flashlight, as shown.
